UNITED STATES PATENT OFFICE.

JOHN STUBBE, OF PITTSBURG, ASSIGNOR TO THOMAS B. KERR, OF ALLEGHENY CITY, PENNSYLVANIA.

BARB-WIRE MACHINE.

SPECIFICATION forming part of Letters Patent No. 326,806, dated September 22, 1885.

Application filed June 3, 1885. (No model.)

To all whom it may concern:

Be it known that I, JOHN STUBBE, of Pittsburgh, in the county of Allegheny and State of Pennsylvania, have invented a new and useful Improvement in Barb-Wire Machines; and I do hereby declare the following to be a full, clear, and exact description thereof.

The object of my invention is to simplify, cheapen, and improve the manufacture of barbed wire. I will describe it with reference to the accompanying drawings, in which—

Figure 1, Sheet 1, is a perspective view of my improved machine, partly in section, on the line $z z$ of Fig. 3. Fig. 2 is a detached perspective view of a part of my machine which produces intermittent motion of parts of the mechanism. Fig. 3, Sheet 2, is a plan view of the machine. Fig. 4 is a sectional view of the intermittent gearing device on the line $x^2 x^2$ of Fig. 5. Fig. 5 is a sectional view on the line $x x$ in a plane at right angles to the sectional plane of Fig. 4. Fig. 6 is a plan view, and Fig. 7 an edge view, of the slotted arms marked $8 8$ in Figs. 2 and 4. Fig. 8, Sheet 3, is a side elevation; and Fig. 9, Sheet 4, a vertical cross-section of the machine on the line $x' x'$ of Fig. 3. Fig. 10 is a similar section on the line $y y$ of Fig. 3. Fig. 11 is a perspective view of the bed-knife detached. Fig. 12, Sheet 5, is a longitudinal axial section of the strand-wire guide and barb-twister, on the line $w w$ of Fig. 3, and on the line $x^3 x^3$ of Fig. 13. Fig. 13 is an end view of the same. Fig. 14 is a perspective view of the end of the rotary wrapper shown in Figs. 12 and 13. Figs. 15, 16, and 17 are end views of the barb-wrapper when it has accomplished a one-seventh, a whole, and one and one-half revolutions, respectively. Fig. 18 is a vertical cross-section on the line $z' z'$ of Fig. 12, showing the position of the barb when it first enters the wrapper. Fig. 19 is a longitudinal vertical section of the moving knife which severs the barbs, showing its relation to the barb-wrapper. Fig. 20 is a horizontal cross-section on the line $y' y'$ of Fig. 19. Fig. 21 is a side elevation of the barb-wrapper shown partly in section. Fig. 22, Sheet 6, is a plan view of the machine shown in connection with a strand-wire twisting and reeling device. Fig. 23 is a side elevation of the same, some of the parts shown in Fig. 22 being omitted

for the sake of clearness. Fig. 24, Sheet 7, is a detached perspective view of the barb-cutting knives and wrapping-tube. Fig. 25 is a detached side view of the moving knife and the blade of the bed-knife, showing their relative situations. Fig. 26 is an enlarged detached view of the part marked c^9 in Fig. 12. Fig. 27 is a longitudinal section of the wrapping-mandrel, omitting the part shown in Fig. 26.

Like letters of reference indicate like parts.

In all the figures of the drawings except Figs. 15, 16, and 17, the several parts of the machine are shown in the position which they occupy when the barb has been inserted between the strands and is being severed.

Referring to the drawings, A A, Figs. 3, 22, and 8, represent the rotatory spools, of ordinary construction, from which the two strand-wires $a a$ are fed into the machine by means of feed-rollers $a' a''$, situate in front of the spools.

Between the feed-rollers and the spools A is a guide-box, a^3 , having a cylindrical bore and an outwardly-flaring mouth. In passing through this box the wires are brought into adjacent alignment before passing between the rollers. The lower feed-roller, a^2 , is driven by a transverse shaft, a^4 , to which it is keyed, and the axis of the upper feed-roller, a^5 , is driven by a gear-wheel, a^6 , which meshes into a pinion, a^7 , on the shaft a^4 , the rotation of the two rollers being such as to draw the wire strands from the spools and to feed them to the other parts of the machine. (See Figs. 3 and 9.) The gear-wheels $a^6 a^7$ are preferably made integral with their respective feed-rollers, as shown in the drawings. (See Fig. 10.) The axes of the feed-rollers are in the same vertical plane, and in order to regulate their pressure upon the interposed strand the upper roller is journaled in bearings B, provided with collars b^1 , movably mounted in upright posts or standards b^2 . A cross-bar, b^3 , connects the upper ends of two vertical standards which form part of the journal-boxes B, and on another cross-bar, b^4 , which connects the ends of the posts b^2 , is mounted a cam, b^5 , which engages the cross-bar b^3 . By depressing a handle, b^6 , of this cam from an upright to a horizontal position the eccentricity thereof will act on the cross-head b^3 , forcing it and the

upper feed-roll on its sliding bearings down against the face of the lower one. The fixed posts b^2 are provided with suitable inclosing coiled springs, b , bearing against the under side of the collars b' , which oppose a resistance to the action of the cam, and, when the pressure of the latter is released, raise the upper roller with its bearings away from the lower roller. The cross-head b^3 is preferably made in form of a bow-spring, as shown in the drawings, so that as strand-wires of unequal gage or any other obstruction pass between the feed-rollers they may cause the rollers to yield somewhat. This device for moving the feed-roller, an edge view of which is shown in Fig. 8, is more clearly illustrated by a rear view in Fig. 9, and by a side view of a similar device for regulating the barb-wire feed-rollers, F , shown in Fig. 8. From the feed-rollers the wire is drawn through a guide tube or box, a^6 , Fig. 3, into a larger guide-tube, c , which is in the same axial line. The guide-tube c is fixed to the bed-plate of the machine by means of a set-screw, c^6 , or otherwise, and on its forward part is a rotatory shell, c' , which forms the barb-wrapping mechanism. This shell is loosely mounted on the guide-tube, so as to be rotatory thereon, and is provided with a circumferential-toothed pinion, c^2 , which gears into and is driven by rotation of a cog-wheel, c^3 . The wrapping shell or mandrel c' is held in place upon the stationary tube c by means of an arm or arms, c^{10} , which bear against the outer end of the pinion c^2 , and hold it against a stationary collar, c^{12} , which abuts against a part of the box or drum 5, hereinafter to be described. The pinion c^2 is either made integral with the barb-wrapping tube c' , or is affixed to it by a set-screw, c^4 . (See Fig. 12.) The latter tube extends somewhat forward of its axial guide-tube c , and at its end is provided with longitudinal open slots c^6 , which are diametrically opposite each other, and are made through the shell of the tube parallel with its axis. At the end of each of these slots is a circumferential slot or recess, c^7 , communicating with its longitudinal slot, and made at right angles therefrom. These recesses are opposite and extend in the same direction, the inner and outer ends of one being diametrically opposite the inner and outer ends of the other, respectively. The length of each recess is about one-seventh of the circumference of the wrapping-tube c' . At the end of the inner fixed guide-tube, c , is a transverse partition, c^8 , which extends diametrically across the tube and tapers backward, thus dividing the latter into two parts, through which the strand-wires pass, and they are thus kept separate and prevented from being twisted together back to this point. The preferable mode of constituting this so-called partition c^8 is by use of the device shown in Fig. 26, which is a small core or plug, c^9 , of the same diameter as the internal diameter of the wrapping-tube, and capable of fitting stationarily therein. The plug is perforated lon-

gitudinally with parallel holes m m' , which taper from their rear to their forward ends, so that the several strand-wires may be easily inserted into them. For the same purpose the rear end of the plug is beveled. As shown in Fig. 12 of the drawings, the forward ends of the stationary guide-tube c and the rotatory wrapping-tube are made in detachable pieces, 70 since these parts should be easily adjustable, and may be needed to be removed for repairs. The inner ends of the longitudinal slots c^6 are preferably in the same transverse plane with the end of the guide-tube c and with the outer 75 end of its partition c^8 , so that the strand-wires opposite to this point are always separated and ready for the insertion of a barb-blank.

The barb-wire is fed from a spool, F^3 , Figs. 3 and 9, into the transverse slots c^7 of the 80 wrapper, between the separated strands, by feed-rollers f F , similar in construction and operation to the strand feed-rollers a' a^2 . The upper barb feed-roller, F , rotates in movable bearings which are so provided with collars 85 f' , mounted upon fixed vertical posts f^2 , as to be capable of being raised or lowered thereon. The posts f^2 have a cross-head, f^3 , and a cam, f^4 , pivoted thereto, and provided with a lever-handle, f^6 , by raising or lowering which the 90 cam is made to act on a transverse spring, f^3 , which is connected with the movable collars f' , thus depressing the latter against the coiled springs f^8 , or raising them therewith. The upper feed-roll, F , is thereby made adjustable 95 relatively to the lower roll, f , in the same manner and for the same purposes which have been described with respect to the strand feed-rolls a' a^2 . These feed-rollers F and a' a^2 are all actuated by the same intermittent gearing, 100 so that when sufficient wire has been fed to make a barb of the proper length the rotation of both sets of rollers stops. A cam, g , Fig. 9, therupon immediately actuates a movable knife, h' , Fig. 19, which severs the barb-blank 105 from its strand, and at the same time the barb-wrapper c' begins to revolve, thereby wrapping the barb around the strand-wires, as shown in Figs. 15, 16, and 17. When the wrapping of the barb has been completed by 110 a one and one-half revolution of the tube c' , the intermittent gearing, before referred to, stops its rotation and starts the rotation of the feed-rollers a' a^2 and f F . The barb thus affixed to the strand-wires then moves from the 115 slots c^6 of the barb-wrapper through the hollow axis d of a rotatory spinner, D , Figs. 22 and 23, to a reel, E , which is mounted in the frame of the spinner transversely to its axis. The rotation of the spinner D is continuous, 120 and serves to twist the two strand-wires, together. The rotation of the reel E intermits with the intermissions of motion of the feed-rollers a' a^2 , and during the motion of these rollers winds the twisted and barbed wire up- 125 on its drum and draws it through the machine. I will explain the operation of these parts more fully hereinafter.

Power is communicated to the machine pref-

erably by a belt which operates a belt-wheel, d' , on the front end of the spinner, and is thence transferred by a crossed belt, d^2 , and another belt, d^3 , from the rear axis of the spinner to a shaft, G. On the shaft G is a cam, g, which operates the knife-lever H, Fig. 1. The end of the arm of the knife-lever is provided with a wheel or roller, h', which rests within a groove on the periphery of the cam, a part of which groove is curved laterally, as shown in Fig. 8, so that when the rotation of the cam brings the end of the lever to the curved part the knife at the other end may be moved backward. The knife-lever H extends above the bed-plate of the machine, and is there provided with lateral arms or trunnions h², which are journaled in bearings i' in the block i, which supports the bed-knife h, Figs. 1 and 11. From the middle part of the trunnions the knife-lever extends in a curved line to clear the other mechanism, and carries at its end a knife, h', which normally is situated in the same horizontal plane and a little forward of the bed-knife h, so that when actuated by the cam g the knife-lever will force its knife toward the bed-knife h against the barb-strand, and will sever the barb-blank.

By reference to Figs. 24 and 25 of the drawings it will appear that the knife-lever H is pivoted at a point which is in about the same vertical line as are the knife h and the roller h', which works in the groove of the cam g. The object and result of this relative situation is to cause the knife h' at the upper end 35 of the lever to be moved in a substantially horizontal right line when the lower end of the lever is actuated by the cam g. The barb is thus cut without the jamming of the two knives. The moving knife h' is secured to 40 the end of the lever H in a vertical slot, h³, and is made adjustable therein by a set-screw, h⁴, which works against the knife from above. The barb-strand wire is fed from the rollers Ff toward the recess c' of the barb-wrapper 45 transversely across the cutting-edge of the bed-knife in an upwardly-inclined direction, so that when cut by the moving knife h' the cut may be lengthwise and beveled to a point, as shown in Fig. 24. This inclination is secured by mounting the guide-tube i² of 50 the barb-strand upon the inclined face of a guide-block, i³, which is affixed to the block i of the bed-knife. The bed-knife is affixed to the block i horizontally and longitudinally 55 with the machine by means of a plate and bolt, i⁴, and at the end of the knife there is a vertical guide-bar, i⁵, Fig. 11, which is mounted within a groove in the front of the knife-block i, and has its end upwardly inclined in the same angle with the angle of inclination of the guide-block i³. This bar is adjustable in its vertical slot by means of a set-screw, i⁶, and it should be so fixed that the wire passing over its inclined end may cross the cutting-edge of the 60 horizontal bed-knife. The adjustability of this guide-bar permits the length of the point of the cut barb to be regulated within certain

limits, for if the bar be raised by its set-screw it will raise the strand until it crosses the outer corner of the horizontal bed-knife, when 70 a long barb will be cut. By lowering the guide-bar in its groove the course of the wire is lowered and made to cross the cutting-edge at points farther inward, thus producing correspondingly shorter barbs. The moving 75 knife and the upper parts of its lever are clearly shown in Figs. 19 and 24 of the drawings, in which it appears that the knife is mounted in the vertical slot h³ at the end of the lever, and has a horizontal cutting-edge 80 in the same plane with the blade of the bed-knife.

On each side of the barb-wrapping tube c' is a wrapping-guide, which extends vertically from the bed-plate of the machine. The outer 85 end of each of these guides h³ h⁴ extends partially around the wrapper c' on a line concentric therewith, and is curved backward on opposite sides of the same. These guides are situated opposite to the diametrical slot c⁶, and 90 the guide-tube i² is so inclined toward the back of the machine (see Figs. 3, 20, and 24) that when the barb is fed through the recess c' of this slot both projecting ends of the barb-blank may lie back of the guides. The intermittent gearing which actuates the pinion c² 95 is so timed that when the wrapping-tube c' stops, the ends of the recesses c' are in the course of the barb-wire. When, therefore, the barb-strand is fed into the wrapping-tube from the feed-rollers, it will pass between the strands a, and will lie diagonally across the longitudinal slot c⁶ and in the ends of these recesses c', so as to project from both sides of the tube, Fig. 13. When at rest in this position, the 100 barb is severed from the strand. During the feed of the barb-strand the strand-wires are being fed from the spools A, while the knife-lever H and the wrapping-tube c' are at rest. As soon, however, as the feed of the barb 105 ceases, the strand-wire feed-rollers stop, the tube c' begins to revolve, and the knife-lever H is actuated by its cam g and cuts off the barb-blank, when the wrapper c' begins to revolve. In cutting the blank the knife h' engages it, forces it back over the face of the bed-knife against the rear side of the recesses c', and holds it there until a partial revolution 110 of the tube in the direction of the arrow carries these recesses away from the blank and 115 causes the latter to be engaged by the sides of the opposite axial slots c⁶. In Fig. 15 of the drawings this operation is illustrated, being there performed by a one-seventh revolution of the wrapping tube or mandrel. The 120 further revolution of the wrapper c' will carry the ends of the blank around the inclosing strand-wires, which are kept stationary by the central guide-tube, c, and its partition c⁸, and will wrap the blank in the manner shown 125 in Fig. 17 of the drawings. When the wrapping-tube c' has reached the position shown in this figure, having completed a revolution and a half, its intermittent gearing will cause 130

it to come to rest. The feed-rollers a' a^2 will then immediately start and carry the cable forward, causing the affixed barb to be drawn out of the wrapper, the barb-wire feed-rollers 5 commence to rotate, and the operations are continued, as before described. During the wrapping of the barb-blank the action of the guides h^3 h^4 is to prevent the blank from overlapping or being wound upon itself, and be- 10 cause the blank is fed back of them to hold it in proper relative position with the cable until after the cutting off of the barb and the commencement of the wrapping process. The ends h^5 and h^6 of the blank in revolving 15 engage the inclined faces of the guides h^4 and h^5 , respectively, and by their inclination are pushed backward so as to wrap helically around the strand-wires. This will be readily understood by reference to Figs. 15, 16, and 20 20 17 of the drawings. The purpose of the trans-verse recesses c^7 is to allow a small interval of time to elapse between the commencement of rotation of the wrapping-mandrel and the begin- 25 ning of the wrapping operation, during which interval the barb-blank is severed. The outer side of the slot c^7 holds the barb-blank during this interval and guides it in 30 its entrance into the wrapper. It is not, how-ever, indispensable, for the slot may, with 35 some disadvantage, be made to extend length-wise entirely to the outer end of the wrapping-tube. As before stated, the barb-wire is fed into the wrapping-tube c^7 so as to rest at the ends of these recesses farthest from the slots 40 c^6 , and consequently a small period of rota-tion of the tube, equal in arc to the length of the recesses c^7 , is idle so far as wrapping the blank is concerned. When the blank en-gages the ends of the recesses, the wrapping 45 action begins. The proper position of the recesses for the entrance of the barb-blank is secured by timing its actuating mechanism to turn the wrapping-tube a number of revolu-tions which is a multiple of one-half. Thus 50 in the manufacture of the style of barb shown in the drawings one and a half revolution is given to the wrapping-tube, and it is clear that at the end of each wrapping operation the recesses c^7 will occupy the same relative 55 positions to the course of the barb-wire, though of course at the end of each period a different recess will be presented toward the barb-strand. During the interval before mentioned the barb is cut, and any slight inaccuracy in 60 the timing of the knife-lever cam g is cor-rected. The moving knife steadies the barb-blank, and adjusts it from an inclined pos-ition into one at right angles to the strand-wires by pressing it against the sides of the 65 slotted recesses c^7 . For this purpose the ec-centricity of the cam g is somewhat elongated, so that the knife may not be retracted im-mediately on cutting the barb.

The construction and operation of the de- 65 vice which produces intermittent motion of the feed-rollers and barb-wrapping mechanism is as follows: The main power-shaft G , which

actuates the knife-lever cam g , is journaled in suitable bearings under the bed-plate of the machine, and terminates in a pinion, g' , which 70 meshes into and drives a gear-wheel, 2. The latter gear-wheel is loosely mounted upon its shaft 3 4, so as to rotate thereon without moving the shaft, and is situated within a drum or casing, 5. On the face of this gear-wheel, and bordering on its periphery, are two studs, 6 7, one being on each face of the wheel and the situation of each being about diametrically opposite the other.

The shaft on which the gear-wheel 2 is 80 mounted consists of two parts, 3 and 4, which are swivel-jointed, so as to be capable of ro-tating independently of each other and inde-pendently of the rotation of the gear-wheel 2.

Keyed to the shaft 3 within the drum 5, and 85 adjacent to the gear-wheel 2, is a plate or disk, 8, which is of the same diameter as the inter-nal diameter of the drum. The plate 8 is sep-90 arated somewhat from the gear-wheel 2 by a sleeve, 10, and is provided with radial slots 95 11 and 12, which are situate diametrically op-posite to each other. In each of these slots is mounted a block or dog, which projects from both sides of the plate. These blocks 13 14 are movable in their respective slots 11 and 12 toward and away from the axis of the plate, and their function is to afford means for en-gaging the stud 6 on the gear-wheel 2 with the plate 8, and thereby communicating the mo-tion of the gear-wheel to the shaft 3, to which 100 the plate is affixed. On the side of the drum 5 next the plate 8 is a fixed annular cam, 15, through which the shaft 3 passes, the cam being concentric with the axis of the shaft. The eccentric part of the cam 15 consists of a 105 depression or recess, 16, preferably situated on its lower side. The cam 15 and slotted plate 8 are so arranged relatively to each other that the movable dogs or blocks 13 and 14 in 110 rotating with the plate bear against the pe-riphery of the cam. Radially opposite to the recess 16 of the cam 15 is another cam, 17, fixed to the shell of the drum 5, and having its eccentricity convex, so as to be a counter-part of the concave eccentricity of the annu-lar cam 15. (See Fig. 4.) On the other side 115 of the plate 8 is a spring-catch, 18, arranged tangentially to the plate 8 and in the path of revolution of the stud of the gear-wheel 2 and of those parts of the movable dogs 13 and 14 120 which project to the inner side of the plate 8. On its under side the spring catch has a notch or recess, which is diametrically opposite to the position of the fixed convex cam 17. The spring-catch 18 is pivotally mounted within a 125 recess, 19, at the upper side of the drum 5, and is provided with a suitable spring, 20, which exerts a downward pressure thereon. The motion of the catch is, however, limited by a stop-pin, 21, which confines it within the 130 recess at such a position that its free end is with-in the path of revolution of the stud 6, so that when this stud in its course reaches the catch it will raise it upon its axis. Thus constructed,

the operation of this device is as follows: Supposing the stud 6 on the side of the gear-wheel 2 to have engaged the dog 14 in the radial slot 12 of the plate 8, its rotation will move the plate 5 and the shaft 3, to which it is affixed, the dog then rotating in contact with the concentric portion of the annular cam 15. When, however, the dog 14 meets with the convex cam 17, it will be moved in the slot 12 by the action of 10 this cam into the opposite concavity 16 in the annular cam 15, thereby disengaging itself from the moving stud 6. At the same instant the other dog, 13, which has been moving with the plate 8 around the concentric part of the 15 cam 15, having engaged the free end of the spring-catch 18, will raise it and slip into its recess. The spring-arm will then fall and engage the dog 13, thereby holding it and stopping the rotation of the plate 8 instantly. (See 20 Fig. 4.) The stud 6, having been released from the dog 14, will continue to rotate freely without moving the plate 8 during a semi-revolution of the gear-wheel 2—*i. e.*, until it reaches the free end of the spring-arm 18—25 when it will raise this arm far enough to release the dog 13 from the recess. It will then engage this dog and will carry it with it in its further rotation, thereby turning the plate 8 and its shaft 3 until the dog is pushed into the 30 recess of the cam 15 and released from the stud by this cam. During this time the dog 14 will have been raised in the slot 12 out of the recess 16 by rotation of the plate 8, and will move around the concentric part of the 35 annular cam and in the path of the stud until it reaches the spring-catch 18, which will grasp it and lock the plate 8, as before described. The locking of the one dog and the release of its opposite by the stud 2 are simultaneous, so 40 that rotation of the plate and of its shaft are instantaneously stopped. The stud 2 then continues to revolve freely for another semi-revolution until it again raises the catch 18 and engages the dog 14, when it will recommence to move the plate 8. The operation is 45 thus continued indefinitely, as before described. The function of the slotted plate 8 is therefore to act as lever-arms for communicating motion from the continuously-moving gear-wheel 2 to the shaft 3, and the function of 50 the movable dogs 13 and 14 is to alternately connect and disconnect the plate from the gear-wheel at successive semi-revolutions of the latter, thus causing regularly intermittent periods 55 of rotation and rest of the driven parts. The shaft 3, which is driven by rotation of the slotted plate 8, extends outside of the drum 5 and terminates in a toothed pinion, g^4 , which meshes into and drives a gear-wheel, g^3 , Fig. 3. The latter gearing is affixed to a longitudinal shaft, g^4 , which is mounted in suitable pillow-blocks on the bed-plate of the machine. This shaft at one end is connected with and drives the lower feed-roller, f , of the barb-feeding mechanism; and this, through cog-wheels $F^1 F^2$, similar to the cogs $a^5 a^7$ of the strand-wire feed-rollers, drives the upper barb- 60 roller, F , Fig. 9. At the other end of the shaft g^4 is a pinion, g^5 , affixed thereto by means of a spline or feather, g^6 , which enables the pinion-wheel to be moved along the shaft within certain limits. The pinion-wheel g^5 meshes into one of the rows of teeth of a crown gear-wheel, g^7 , whose shaft a^8 extends transversely across the machine and drives the lower feed-roller, a^2 . The side of the crown-wheel g^7 has 70 two concentric series of gear-teeth, g^8 and g^9 , Fig. 3. By moving the pinion-wheel g^5 on the feather g^6 until its teeth engage the inner series of teeth on the crown-wheel, it is evident that rotation of the shaft g^4 will impart a more rapid rotation to the crown-wheel shaft and to the feed-rollers $a^8 a^2$ than if the pinion meshes into the outer series of teeth. By thus changing the position of the pinion upon the 75 shaft g^4 a faster or slower rotation may be given to the strand-wire feed-rollers, and the length of wire fed during each period of their rotation increased or diminished. It will then be apparent that the feed-rollers $a^8 a^2$ and F are all actuated by the rotation of the intermittently-moving plate 8, that the motion of these parts is synchronous, and that they operate during one half of the rotation of the main power-shaft G and are at rest during the 80 other semi-revolution. While the strand-wires are passing through the guide-tube c , the barb feed-rollers feed their wire through the slot c^1 and between the separated strands. The length of the strands fed relative to the 85 length of the barb-blank may be determined by the relation of the diameters of their feed-rollers, and is regulated by changing the gearing of the pinion g^5 from one series of crown-wheel gear-teeth to the other. During the 90 feed of the strand-wires and of the barb-wire the barb-wrapping mandrel c' is stationary; but immediately on the stoppage of these feeds the mandrel begins to revolve and wraps the barb around the strands. The alternate motion 95 of these parts is secured by a duplication of the intermittent gearing device formerly described, and is illustrated in Fig. 1. The shaft 4, which is swivel-jointed to the end of the shaft 3 within the drum 5, is provided with 100 radially-slotted plate 9, similar in construction to the radially-slotted plate 8, before described, but situate on an opposite side of the revolving gear-wheel 2. The slots of the plate 105 9 are also provided with dogs or blocks 22 and 23, which are movable radially within the slot and project from both sides of the plate. On the side of the drum is an annular cam, 24, having a recess or concavity similar to the recess 16 of the cam 15, the periphery of 110 which cam is in the path of rotation of the inner end of one of the projections of the dogs, so that as they move around it its concentric part may keep them out in their slots in the path of the stud 7 on the gear-wheel 2. 115 At the base of the casing and opposite to the recess of the cam 24 is a convex cam, 25, and at the top of the drum, parallel with the spring-catch 18, is a spring-catch, 27, having a recess 120 130

adapted to catch and confine one of the projections of the blocks 22 and 23. The plate 9 is held away from the side of the gear-wheel 2 by a sleeve, 26. The parts in this segment 5 of the drum 5 are situated in the same relative positions and are in the same horizontal plane as their corresponding parts in the segment first described, the plates 8 and 9 being parallel. The only difference is, that the stud 10 7 on the one face of the gear-wheel 2, which operates the dogs 22 and 23, is diametrically opposite to the situation of the stud 6 on the other face of the gear-wheel. The plate 9 is operated intermittently by the stud 7 in the 15 same manner as the plate 8 is operated by the stud 6. The consequence is, that at the instant that the stud 6 has carried its dog 14 into contact with the convex cam 17 and has been disengaged from it, and the plate 8 has been 20 locked by the engaging of the spring-catch 18 with the dog 13, the stud 7 on the opposite side of the plate will have raised its spring-catch 27 and will have released and engaged the confined dog 22. During the next semi- 25 revolution of the gear-wheel 2 the stud 6 will move freely without rotating the plate 8 or its shaft 3, while the stud 7 will turn the plate 9 and the shaft 4, to which it is affixed, because of the engagement of the latter stud with the 30 block 22. At the end of this period the block 22, having engaged the convex cam 25, will be forced into the eccentric recess in the annular cam 24, and thus disengaged from the stud 7, while the opposite block, 23, having been raised 35 from the recess onto the concentric part of the cam by rotation of the plate, will have reached and become locked by the notched spring-arm 27. This will stop the plate 9 and its shaft 4 instantly; but the stud 6, having by this time 40 reached the spring-catch 18, will release and engage the block 14 and recommence to rotate the plate 8 and its shaft 3. On the end of the shaft 4 which projects from the drum 5 is the cog-wheel c^3 , which drives the barb-wrapping 45 mandrel c' . It is therefore clear that the continuous rotation of the shaft G, acting on the gear-wheel 2, will alternately actuate the mandrel c' and both pairs of feed-rollers. The 50 mandrel will be at rest while one semi-revolution of the gear-wheel 2 impels the plate 8 and the feed-rollers; but as soon as this semi-revolution is complete and the feed-rollers have been stopped the other semi-revolution of the wheel 2 will actuate the plate 9 and the 55 mandrel c' .

As shown in the drawings, the gear-wheel c^3 is of three times the circumference of the pinion c^2 on the mandrel c' , so that the semi-revolution of the gear-wheel may rotate the mandrel once and a half to produce a barb of the character shown in the drawings, though of course the intermediate gearing may be so timed as to rotate the mandrel a greater or less number of times to produce barb-wire of 60 a different variety. The cam g is adjusted upon the shaft G so that its lateral eccentricity will engage the end of the knife-lever

H simultaneously with the commencement of the stud 7 to turn to the plate 9 and revolve the mandrel c' , and the eccentricity is made 70 long enough to cause the knife to hold the barb-blank against the inner side of the recess c^1 until the mandrel has made a one-seventh revolution, as before described.

The operation of twisting the wire strands 75 is performed by the continuous rotation of the rotary spinner D, to the reel E of which the strands are secured. The revolution of the spinner is preferably in the opposite direction to that of the mandrel c' , this being secured by 80 crossing the belt d^2 , as shown in the drawings. The function of the reel E is to wind the twisted and barbed wires upon its drum and to draw them through the machine. Its rotation is influenced by that of the feed-rollers 85 $a' a^2$, so that when they stop the reel stops also. This is done as follows: The front journal-shaft of the rotary spinner D, which is the axis of the belt-wheel d' , is hollow. Through it a horizontal shaft, e^5 , extends to the 90 end of the machine, where it is provided with a wheel, e^6 , bearing on the surface of which is a brake, e^7 , or similar friction device for retarding its revolution. The other end of the shaft e^5 within the periphery of the spinner 95 is provided with a miter-wheel, e^8 , which gears into a similar pinion-wheel, e^9 , the axis of which is journaled to the sides of the spinner-frame. The latter gearing is connected by suitable gear-wheels, e , to the axis $e' e'$ of the reel E. Ordinarily the brake-wheel e^6 is held stationary by the friction of the brake e^7 . Revolution of the spinner D will carry the beveled periphery of the miter-wheel e^8 around that of the stationary cog e^9 , and will 100 impart a rotary motion to the former wheel and to its shaft. This also rotates the gear-wheels e , and they in turn revolve the reel E on its axis and cause the twisted strands to be wound thereon. One of the reasons for this 105 arrangement of the reel is to compensate for its increasing diameter as the wire is wound upon it. This increase causes the reel to draw the wire more rapidly from the machine, and if it were driven directly by rotation of the spinner D would break the strip or the machine. When, however, the strain on the twisted strands caused by its increased 110 rapidity of winding has reached a certain point great enough to overcome the resistance 115 of the brake e^7 , the wheel e^6 will turn with the miter-wheel e^8 upon its axis. In such case it is clear that the miter-wheel e^8 will turn around the periphery of the wheel e^9 without the resultant rotation of the reel which I have 120 described. When the strain on the strands is slackened by the feed-rollers $a' a^2$, the wheel e^6 and miter-wheel e^8 come to rest and the reel commences to revolve freely. The effect of 125 this is to keep the strands in a constant state 130 of tension and in proper condition for the adjustment of the barbs. Another important result of this arrangement is to stop the reel when the motion of the feed-rollers $a' a^2$ stops.

The stoppage of these rollers is positive, since they are actuated by gearing a^4 a^5 , and as the upper feed-roller is pressed upon the lower one their friction will exert a considerable strain 5 on the wire strand. This strain will also be exerted on the reel E, and will cause the friction-wheel e^6 to overcome its brake e^7 and turn, thereby stopping the reel until the feed-rollers again begin to move. The pressure of the 10 brake e^7 upon the wheel e^6 is regulated by a cord, e^8 , which is connected with the brake, and passes thence to a suitable brake-lever or ratchet.

In Fig. 9 of the drawings I have shown 15 means for directing the course of the barb-blank into the wrapping-tube. It consists in pivoting the guide-block i^3 by means of a pivot, i^5 , on which it may be moved, so as to give its surface any desired inclination.

20 What I claim as my invention, and desire to secure by Letters Patent, is—

1. The combination, in a barb-wire machine, of a hollow rotatory wrapper for wrapping the barbs on a cable whose strands are arranged 25 longitudinally within the wrapper, mechanism for feeding the strands through the wrapper, barb-feeding mechanism for feeding the barb-wire into the wrapper and between the strands, and the flexed barb-guide 30 pieces h^3 h^4 , substantially as and for the purposes described.

2. The combination of the rotatory wrapper of a barb-wire machine, having slots for the entrance and exit of the barb-blank, knives 35 for severing said blank after it has been fed into the wrapper, the moving knife arranged to operate transversely to the course of the barb-strand and longitudinally with said wrapper for the purpose of cutting, moving, 40 and holding said barb, substantially as and for the purposes described.

3. The combination, with feed-rollers for feeding the barb-wire toward the cable-strands, a knife for severing the same, and a

wrapper for securing the barb-wire to the cable-strands, of a guide-block, i^3 , movable, so as to change its inclination to the horizontal, for the purpose of directing the barb-strand relatively to the wrapper and regulating the length of the point cut thereon, substantially 45 as described.

4. The combination, with the feed-rollers of a wire-barbing machine and a shaft for driving the same, of a crown-wheel mounted on said shaft and a pinion movable from one 50 series of teeth on said wheel to another, substantially as and for the purposes described.

5. A rotatory wrapping-tube for barb-wire machine, having a hollow tube for passage of the strand-wires, and axial slots e^6 and elongated transverse slots e^7 , in combination with feeding mechanism for causing barb-wire to be fed thereinto, substantially as and for the purposes described.

6. The combination, in a barb-wire machine, 65 of two revoluble shafts, 3 and 4, each provided with lever-arms having lugs or blocks capable of motion toward or from the axis of revolution, with an interposed driving-disk, 2, having driving-studs on each side and cams 70 for throwing the lugs or blocks into and out of the path of revolution of the studs, whereby an intermittent rotation is imparted to the shafts, mechanism for feeding the cable-strands, and mechanism for feeding the barb-strand, both of said mechanisms being connected with and actuated by one of said revoluble shafts, and mechanism for wrapping the barb actuated by the other of said shafts, whereby a regularly-intermittent rotation is 75 imparted to each of these parts, substantially as and for the purposes described.

In testimony whereof I have hereunto set my hand this 1st day of June, A. D. 1885.

JOHN STUBBE.
